[57] CLAIM

The ornamental design for a plumbing fixture cover, as shown and described.

DESCRIPTION

FIG. 1 is a perspective view taken from the top, front and right side of a plumbing fixture cover showing our new design;

FIG. 2 is a top plan view thereof;

FIG. 3 is a right side elevational view thereof, the left side being a mirror image of the right side shown;

FIG. 4 is a front elevational view thereof;

FIG. 5 is a rear elevational view thereof;

FIG. 6 is a bottom plan view thereof;

FIG. 7 is a perspective view taken from the top, front and right side of a second embodiment thereof;

FIG. 8 is a top plan view of FIG. 7;

FIG. 9 is a right side elevational view of FIG. 7, the left side being a mirror image of the right side shown;

FIG. 10 is a front elevational view of FIG. 7;

FIG. 11 is a rear elevational view of FIG. 7; and

FIG. 12 is a bottom plan view of FIG. 7.

The broken line representation of a toilet in FIG. 1 and a bidet in FIG. 7 are for purposes of illustration only and form no part of the claimed design.
